BOX

Harry V. Marsh, Chicago, Ill.

Application April 14, 1932, Serial No. 605,175

9 Claims. (Cl. 229—17)

This invention relates to a container and has to do more particularly with the provision of a spout for a box of cardboard or the like.

It is an object of the present invention to provide a box with scores and creases in the material whereby to close the top of a box with the formation of a spout when the material of the top is unfolded from its closed position.

Another object of the present invention is to provide a top closure for a box capable of forming a collapsible spout.

Still another object of the present invention is to provide in a single blank piece of material scores and creases adapting the material to be folded into a box having a collapsible spout closing an opening therein.

These objects and other objects made manifest in the description to follow are obtained by the novel construction and improved arrangement of the parts embodying the invention and shown in the accompanying drawing hereby made a part of this specification in which:

Figure 1 is a fragmentary plan view of a blank showing the sides and end sections for a box;

Figure 2 is a perspective view of a box embodying the invention when in an open position;

Figure 3 is a view similar to Figure 2 but with the material in position for closing the opening in the box;

Figure 4 is an internal view of the box taken at the section indicated by the line 4—4 of Figure 3;

Figure 5 is a fragmentary plan view of a blank of material for forming a different form of the invention;

Figure 6 is a perspective view of a box and spout articulated from the blank shown in Figure 5;

Figure 7 is a section view illustrating construction details and taken along the line 7—7 of Figure 6 when the spout is in the retracted position; and

Figure 8 is a view taken in cross-section at the line 8—8 of Figure 7.

Like reference characters indicate the same parts in the drawing and in the following description.

The fragment of a blank illustrated in Figure 1 shows an end structure for a box. Such blank includes a number of scores and extensions.

The latter may be folded to form the end of a box in the same manner as the flaps of a conventional box with a closed end.

Scores 10, 11, 12 and 13 divide the blank 14 into parts forming the sides 15, 16, 17 and 18 of the box. Blank 14 may be composed of a

fibrous material like cardboard. Extending from side 15 is a narrow strip 19 to receive adhesive for securing the blank in an assembled position.

Separated from side 15 by a score 20 is an extension 21 the free edge of which is notched 60 at 22. Side 16 has an extension 23 in which an incision 24 defines a tongue 25. A score 26 in alignment with score 20 separates extension 23 and the side 16.

The side 17 has an extension 28 separated 65 therefrom by a score 27 in alignment with score 26. Extension 28 has a central section 28a in the form of a tongue and two side sections, the side sections being separated from the tongue 28a by scores 29 in alignment with the contiguous 70 edge of the tongue. Another score 30 divides each side section into sections 31 and 32. Extension 33 projects from side 18 and is divided therefrom by score 34. A tongue 35 like tongue 25 but opposed thereto is separated from the body of the 75 extension 33 by an incision 36.

The box is assembled by arranging the four sides 15, 16, 17 and 18 as the four parallel sides of a parallelepiped. The narrow strip 19 is placed within the structure adjacent side 18 and is secured by any suitable adhesive material. The bottom part of the box (not shown) may be of standard construction and assembled in the usual manner.

The extensions 23 and 33 are folded 90 degrees 85 inwardly of the box. The small section 19a at the top of the strip 19 is folded inwardly with the extension 33. Extensions 23 and 33 are of such a length that the tongues 25 and 35 are in close proximity when said extensions are folded 90 inwardly. The extension 21 is folded to rest upon the top of the previously folded extensions with the edges of notch 22 coinciding with the space between the tongues 25 and 35 and the side 17 of the box.

The sectors 31 are brought inwardly and bent 180 degrees about the scores 29, to bring them contiguous to the main body of the extension 28. The sectors 32 are articulated 180 degrees in the opposite direction about the creases 30. 100

When the extension 28 is folded on the score 27 to rest upon the top of the box, the faces of the sectors 32 exposed in Figure 1 are within the notch 22 and lie upon the faces of the tongues 25 and 35. This is best shown in Figure 2. The 105 outer edges 37 of the sectors 32 are disposed in confronting relation to the edges 38 of notch 22.

The faces of the sectors 32 are secured to the tongues 25 and 35 by suitable adhesive material. The extension 26 serves as the bottom wall of a 110

folding spout for the box while the sector sections 31 and 32 provide the sides of the spout. Tongues 25 and 35 are flexible and are extended outwardly of the box by extending section 28. 5 Thus the tongues 25 and 35 only partially close the opening to the box and assist in the apportionment of articles being emptied therefrom.

When it is desired to close the opening in the box, the extension 28 is bent over the top in the 10 manner shown in Figure 3. In packaging a product within the box, the tip 28a may be secured to the extension 21 in a manner to hold the closure formed by the extension 28 in place until manually broken.

15 Figure 5 and the higher numbered figures illustrate a modified form of the invention. There is illustrated in Figure 5 a blank 40 of material similar to that shown in Figure 1. Sides 41, 42, 43 and 44 are separated by the scores 45, 46 and 20 47. A section 48 at the edge of the side 44 is separated therefrom by a score 49.

The strip 48 has a short extension 50 which cooperates with the strip 48 to hold the box in assembly. Sections 41 and 42 have extensions 25 51 and 52. These sections are separated therefrom by scores 53 and 54, respectively.

30 Scores 55 obliquely disposed in the extension 52 separate tongues 56 from that extension. The outer edges of the tongues 56 are cut away to provide an inwardly extending opening 57 therebetween.

From the side 43 projects an extension 58 with a score 59 therebetween. Creases 60 extend from the lower corners of the extension 58 inwardly to 35 divide its middle section from two sectorlike sections 62 and 63 which are separated one from another by score lines 61. The central portion of the extension 58 has a tip 64 with an arcuate edge projecting therefrom, and is separated therefrom by score 64a.

40 From the side 44 and separated therefrom by a score 65a is an extension 65 having at its edge a notch 66 having edges 67, 68, and 69.

In assembling this type of box, the blank is 45 folded into parallelepiped and adhesive disposed upon extension 48. Extension 51 is bent within the plane of the opening at the top of the box. Section 52 is folded over section 51 and is covered by extension 65 folded upon score 65a. The edges 67 and 68 are then parallel to the scores 55 of tongue 56. Sectors 63 are then attached to the tongues 56 by adhesive and are guided into position by placing the edges 70 thereof against the edges 67 and 68 of the extension 65. At this time, 55 the box will be assembled as shown in Figure 6, with the extension 58 and the tip 64 thereof projecting in the manner of a spout. Sectors 62 and 63, arranged somewhat in the manner of bellows, form sides for the spout.

60 The spout is closed over the opening 37 by bending it inwardly at the fold line 59 to displace the sections 62 and 63 about their intermediate creases 61 in the fashion of a bellows and to bring the extension 58 within the plane of the opening. Anterior to the closing of the opening the tip 64 of the extension may be bent normal thereto along the score 64a so that it may be inserted into the slit-like opening 55a as shown in Figure 7.

70 What is claimed to be new and desired to be secured by Letters Patent of the United States is:

1. In a container having walls and an opening, an extension from a wall thereof providing apportioning tongues projecting oppositely in parallelism with and contiguous to the plane of said

opening, and a second extension from a second wall of said container creased for folding into a spout for said opening, said spout being collapsible into a closure adapted to fall substantially within the plane of said opening.

80 2. In a container formed from a sheet of material and having walls and an opening, extensions from opposed walls of said container providing apportioning tongues to project oppositely into a plane alongside of the plane of said opening, a third extension from a wall of said container and scored for folding into a spout for said opening, said spout being adapted to collapse into a closure substantially within the plane of said opening for closing said container.

85 3. In a container formed from a single sheet of material and having walls and an opening, an extension from a wall of said container providing apportioning tongues for projecting oppositely into a plane parallel to and contiguous to the plane of said opening, a second extension from a wall of said container and scored to form a spout for said opening, said spout being adapted to fold into a flat body disposable substantially into the plane of said opening as a closure for said container.

90 4. In a container formed from a sheet of material and having walls and an opening, opposed confronting apportioning tongues projecting over a portion of said opening, an extension from a wall of said container scored for folding into a spout for said opening, and having a tip, said spout being collapsible into a flat closure falling substantially within the plane of said opening, and said tip being disposed normally to said opening for frictionally coengaging said tongues and the edge of said opening.

95 5. A container comprising a sheet of material divided into walls for said container, one of said walls having an opening therein, apportioning tongues projecting oppositely in parallelism with and substantially into the plane of such opening, and an extension from said sheet of material, said extension being scored for ready folding to form a spout for such opening, the material of said 100 spout being foldable into a flat body disposable into a plane parallel to and adjacent to the plane of said opening and providing a closure for said opening.

105 6. A container comprising walls of sheet material, one of said walls having an aperture therein, confronting apportioning tongues of the material of said container projecting oppositely across such aperture within a plane contiguous thereto, there being a section of such material 110 having scores extending from along the edges of said opening to form a spout for said opening, said section being foldable into a relatively thin compact body disposable over said opening for the closure thereof.

115 7. A container of a single sheet of material and having one wall of a plurality of laminations of said sheet, one of said laminations having an opening therein for discharge of the contents of said container, apportioning tongues in another of said laminations and extending across a portion of such opening, and a third lamination forming a spout for said opening, said third lamination having fold lines and being foldable along such lines for the collapse of said spout into a flat body providing a closure for such opening.

120 8. An end structure for a six-sided container formed from a single sheet of material, said end structure including layers of such sheet material extending from the sides of said container, one of

said layers having an opening therein into said container, a second of said layers comprising apportioning tongues extending across such opening in parallelism with the plane thereof, and a 5 third of said layers forming a spout having sides, there being in said spout-forming layer scores separating the sides from the main body of said spout, and said spout and side members thereof being collapsible to effect a flat member dispo-
10 able over such opening for the closure thereof.

9. A container of a single sheet of material

and having a plurality of walls, one of said walls having an opening therein, tongues formed from said sheet of material and extending across a portion of such opening in a plane contiguous to and parallel to the wall having an aperture therein and an extension of such material folded into a spout for said opening, said spout being collapsible into a plane body for closing said opening in said container.
